(57) **CLAIM**

The ornamental design for a floating chair, as shown.

DESCRIPTION

FIG. 1 is a perspective view of the floating chair in accordance with my new design.

FIG. 2 is a top plan view thereof.

FIG. 3 is a bottom plan view thereof.

FIG. 4 is a right-side elevation view thereof.

FIG. 5 is a left-side elevation view thereof.

FIG. 6 is a front elevation view thereof; and,

FIG. 7 is a rear elevation view thereof.

The broken lines and the areas within them in FIGS. 1 and 2 depict portions of the floating chair that form no part of the claimed design.
